United States Patent [19]

Knute

[11] Patent Number: Des. 277,938

[45] Date of Patent: ** Mar. 12, 1985

[54] COMBINED CLINICAL TEMPERATURE PROBE AND ELECTRODE

[75] Inventor: Wallace L. Knute, Del Mar, Calif.

[73] Assignee: Camino Laboratories, San Diego, Calif.

[**] Term: 14 Years

[21] Appl. No.: 415,550

[22] Filed: Sep. 7, 1982

[52] U.S. Cl. D10/60

[58] Field of Search D10/57, 60, 102, 103, D10/78; 374/179, 183, 185, 208, 209, 159

[57] CLAIM

The ornamental design for a combined clinical temperature probe and electrode, substantially as shown.

DESCRIPTION

FIG. 1 is a perspective view of a combined clinical temperature probe and electrode showing my new design;

FIG. 2 is a top plan view thereof;

FIG. 3 is a right end elevational view thereof;

FIG. 4 is a left end elevational view thereof;

FIG. 5 is a front elevational view thereof;

FIG. 6 is a bottom plan view thereof;

FIG. 7 is a rear elevational view thereof.
